AUTOMATIC DRAFT OPERATOR FOR
FURNACES

Arthur F. H. Weiss, Irvington, N. J.

Application November 21, 1939, Serial No. 305,535

2 Claims. (Cl. 161—8)

My invention relates to an automatic draft operator for furnaces and has as one of the principal objects thereof the provision of an apparatus so constructed and arranged as to operate the various drafts on a furnace at a predetermined period whereby to open or close said drafts as desired.

Another object of my invention is to provide a device of the above described character which is simple in construction, durable in use, efficient in operation, easy of installation, economical in manufacture, and capable of being attached to furnaces already in use without modifying the same.

Other objects and advantages will be apparent from the following description, appended claims and annexed drawings.

Referring to the drawings wherein like reference characters designate like parts throughout the several views:

Figure 1 is a front elevation of a furnace illustrating my invention as applied thereto.

Figure 2 is an enlarged side elevation of a portion of the apparatus.

Figure 3 is a sectional view taken on the line 3—3 of Figure 2.

Figure 4 is an enlarged side elevation of one of the weight supports.

Figure 5 is a detail sectional view taken on the line 5—5 of Figure 4.

Figure 6 is a side elevation of the upper portion of the furnace disclosed in Figure 1 and illustrating the manner in which my invention is applied or connected thereto.

In practicing my invention, as illustrated in the drawings, I employ a support or shelf 5 arranged in proximity to a furnace or boiler 6, the latter being of an ordinary construction and provided with the usual flue, ash pit and fire box dampers 7, 8 and 9 respectively. The upper portion of the furnace 6 is formed with a smoke dome or passage 6a having a rearwardly extending section 6b connected to the end of a smoke pipe 1a constituting the flue and in which is mounted the flue damper 7.

The ash pit damper 8 is of the pivot type and controls the opening through the ash door in the usual manner. The ash pit damper 8 is provided on the exterior thereof with a laterally extending arm 10 for operating the same and the outer end of said arm has connected thereto the lower end of a regulating chain 11. The upper end of the chain 11 is detachably connected to the front end of an arm 12, the latter being pivotally connected between its ends to a thermostat T for

operation thereby in the usual manner. The rear end of the arm 12 has connected thereto the upper end of a chain 12a, the lower end of which is connected to a draft door 6c pivotally mounted on the rear section 6b of the dome 6a for controlling the draft opening in the section 6b.

It is to be understood that the thermostat and associated parts heretofore described are of an ordinary construction and form no part of the present invention per se. Furthermore, the thermostat is utilized for regulating the ash pit damper 8 and the door 6c to maintain the furnace operating at a desired temperature.

15 The fire box damper 9 is of the slide type and has connected thereto, by means of a hook, the lower end of a cable 14 trained through a screw eye 15 secured in the upper face of a support positioned adjacent the boiler 6. The upper section of the cable 14 is trained through a pair of screw eyes 16 and with the upper end connected to the eyed end of a pair of weights 17 supported on a deck 18, one end of the latter being hinged to a support bracket 19 or the like secured to the 20 rafter of the ceiling above the boiler 6. The opposite end of the deck 18 is normally maintained in raised position through the medium of a seat or projection formed on the lower end of a lever 20 pivoted to the support bracket 19 at one end 25 thereof.

30 The lower end of the lever 20 is engaged by a spring 21 normally urging said lever into supporting engagement with the deck 18. Obviously, pivoted motion imparted to the lever serves to permit downward movement of the deck 18 and consequent lowering of the weights 17 for a purpose hereinafter more fully set forth. The other weight 17 has attached thereto the upper end of a cable 22 trained through a pair of screw eyes 23 and the lower end of said cable 22 is provided with a hook adjustably connecting the same to the chain 11. Obviously, lowering of the weights 17 serves to effect raising of the lower ends of the cables 14 and 22 and a consequent 35 operation of the dampers 8 and 9. Adjacent the bracket 19 is a similar bracket 24 mounted on the rafter and having hinged thereto a deck 25 normally supported in raised position by means of a lever 26 of a like construction and operation 40 as the lever 20.

45 Mounted on the deck 25 is a weight 27 having attached to the eyed end thereof the upper end of a cable 28 trained through a pair of screw eyes 29. The lower end of the cable 28 is connected 50 to the operating arm 13 of the damper 7. The

upper ends of the levers 20 and 26 have connected thereto the upper end of an operating cable 30 trained through a screw eye 31 secured in the rafter and the lower end of said cable 30 is connected to the eyed end of a weight 32 mounted on one end of a platform 33, the latter being pivoted between its ends to the upper end of a support 34 fixed to one end of the shelf 5.

The opposite end of the platform 33 normally engages the hooked end 35 of a bell crank lever 36. The opposite end of the bell crank lever 36 has connected thereto the lower end of a cable 37 trained through a screw eye 38 secured to the shelf 5. Between the ends thereof, the shelf 5 is provided with a support S of an inverted L-shaped configuration having secured thereto a screw eye 39 through which is trained the upper end of the cable 37. Said upper end of the cable 37 is connected to the cross piece 40 integrally fashioned on the ends of a pair of spaced arms 41. The opposite or lower ends of said arms 41 are coiled and secured to a plate 42 fixed to the vertical section of the support S. The coil sections of the arms 41 constitute coil springs for urging the cross piece outwardly and away from the plate 42. The upper end of the plate 42 has pivoted thereto an arm 43 normally overlying and engaging the cross piece 40.

The lower end of the arm 43 is provided with a slot 44 through which extends a downwardly and outwardly inclined end section of a bell crank lever 45, the opposite end of which is fixed to a slide 46 extending through the lower end of the plate and vertical section of the support S as clearly illustrated in Figure 2 of the drawings. The inclined end section of the bell crank lever 45 serves to maintain the arm 43 in overlying relation with the cross piece 40 and against the tension of the coil springs on the ends of the arms 41, thereby precluding outward movement of said arms.

The opposite end of the slide 46 has connected thereto one end of a cable 47 which is trained through the eye of a support 48 secured to the shelf 5. The opposite end of the cable 47 is connected to the hammer 49 of an alarm clock 50 from which the bell has been removed. Said alarm clock 50 has secured thereabout a strap 51, the ends of which are secured by means of bolts or the like 52 to said shelf. Obviously, when the hammer of the alarm clock is operated it serves to effect operation of the bell crank lever 45 through the medium of the cable 47 and slide 46, thereby releasing the lower end of the arm 43 and permitting outward movement of the arms 41. Outward movement of the arms 41 serves to operate the bell crank lever 36 through the medium of the cable 37 and this operation effects disengagement of the hooked end 35 of the bell crank lever from the end of the platform 33. Upon the end of the platform 33 being disengaged from the bell crank lever 36 said platform is pivoted in a manner to discharge the weight 32 downwardly, effecting operation of the cable 30. Operation of the cable 30 serves to operate the

levers 20 and 26 and subsequent operation of the decks 18 and 25, heretofore described.

From the foregoing it will be apparent that when the device is set and operated in the foregoing manner the various drafts of the furnace may be operated at a predetermined period for raising or increasing the temperature of the fire in the boiler.

It is obvious that the invention is not confined to the herein described use therefor as it may be utilized for any purpose to which it is adaptable. It is therefore to be understood that the invention is not limited to the specific construction as illustrated and described, as the same is only illustrative of the principles of operation, which are capable of extended application in advance forms, and that the invention comprehends all construction within the scope of the appended claims.

What I claim is:

1. The combination with a heater provided with draft-controlling dampers, of a clock mechanism having a swinging hammer, an operating spring, means for releasably holding the said spring in retracted inoperative position, means connected with the hammer and engageable with the spring holding means for releasing the spring upon operation of the hammer, a pivoted support member, a controlling weight mounted on the said support member, a pivoted latch for releasably holding the support member in weight supporting arrangement, a flexible element connecting the latch with the operating spring for releasing the latch when the spring is released, a plurality of weights attached to the heater dampers for operating the same, a pair of pivoted members releasably held in position to support the said weights, and means for releasing the said damper actuating weights upon release of the controlling weight.

2. In combination with a heater having a plurality of draft controlling dampers, a flexible operating element connected to each of the dampers, an auxiliary weight attached to each of the flexible elements and adapted to open the dampers upon release of the weights, a pair of pivoted support members for supporting the auxiliary weights in damper closure positions, lever elements for releasably supporting the pivoted members in elevated weight supporting arrangement, a main weight connected with the said lever elements to actuate the latter for releasing the pivoted members when the said main weight is released, a pivoted member operable to support the main weight, a pivoted latch member for releasably holding the last mentioned pivoted member in weight supporting position, an operating spring connected with the latch member for swinging the latter to main weight releasing position, means for releasably holding the operating spring in retracted position, a clock mechanism having a swinging hammer, and mechanism connected with the said hammer and with the spring holding means for releasably maintaining the latter in spring retracting position.

ARTHUR F. H. WEISS.
